UNITED STATES PATENT OFFICE

HOMER T. DARLINGTON, OF WEST CHESTER, PENNSYLVANIA, ASSIGNOR, BY MESNE ASSIGNMENTS, TO OIL CORPORATION OF AMERICA, A CORPORATION OF DELAWARE

HYDROCARBON TREATMENT PROCESS AND APPARATUS

Application filed April 25, 1927. Serial No. 186,462.

My invention relates to a new and useful process and apparatus for distilling, cracking and otherwise treating liquid hydrocarbons. The nature of my invention will more 5 clearly appear by reference to the accompanying drawing and the description which follows of the apparatus, specially designed and invented by me for use in my process.

In the drawing:

10 Figure 1 shows a side elevation of a preferred form of apparatus; and

Fig. 2 is a top view of the same.

The same figures indicate like parts in drawing.

15 In Fig. 1 an elongated tubular member or chamber 1 with means of admitting charging stock 15, means of introducing gas or steam or a treatment or other addition agent 16, and means for the withdrawal of heavier

20 products 17, is connected to chambers 3 and 10 by a plurality of heating tubes in two groups 2 and 11. The chambers 3 and 10 give into pump connectors 4 and 9 respectively, putting them into communication with

25 the centrifugal pump 5 having an impeller 6 operated through the shaft 7 by the motor 8. The heating tubes 2 and 11 are provided with any suitable means of heating, such as a firebox or furnace or heat flues therefrom 30 surrounding them.

12 is a zone in the elongated tubular chamber 1, or it may be added or supplemental chamber, in which vapors and gases separate and from which they pass to any suitable

35 means of cooling and separating. In this passage, baffles 13 to arrest moisture, and cooling coils 14, or either of them, may, or may not, be provided as preferred. 18 is a zone in which solids may settle.

40 While I prefer to use a centrifugal pump having an impeller as a means of promoting circulation any other means of causing positive controlled circulation may be employed instead.

45 To increase variations in rapidity of circulation and in pressures during circulation, I may have a greater number of tubes in one group of heating tubes than in the other, and I may so proportion the chambers 3 and 10 and pump connectors 4 and 9 that rates

of circulation and intensity of pressure in them will differ from that in other parts of the apparatus and will differ in one chamber and connector (say 3 and 4) from that in the other chamber and connector 9 and 10. 55

The use of an impeller 6 to promote and dominate circulation also produces certain definite pulsations and consequent vibrations in intensity of pressure and in speed of circulation. These variations in pressure are 60 due in part to the forces of suction and pressure which are developed on opposite sides of the impeller or pump. Incidental to these various changes in pressure and rate of circulation, eddies and currents are induced in 65 the hydrocarbons, not present when the flow is a direct stream, which help to keep disassociated carbon in suspension and to facilitate and increase cracking.

In operation, charging stock, either cold 70 or preheated, is fed continuously or intermittently into the chamber in the tubular member 1 and is forced by the impeller 6 to flow through heating tubes 2 where it is raised to a temperature conducive to cracking, and thence flows continuously through the chamber 3, pump connection 4, pump 5 and back through the pump connection 9 chamber 10, tubes 11 into the chamber in the tubular chamber 1 where vapors and gases ascend and 75 are drawn off and the hot oil circulates through the chamber and, less any portion that may be drawn off (through 17), is recycled.

80 In this cycling and recycling, the hydrocarbons are heated to a temperature conducive to cracking, varying slightly in different parts of the apparatus, circulate rapidly at varying rates, and are subject to pressure also conducive to cracking, varying frequently and at times abruptly. These variations in pressure and rapidity of circulation, I find 85 materially aid the formation of low-boiling-point hydrocarbons from higher-boiling-point hydrocarbons. I have also found that the shock of contact when cold oil is forced into hot oil rapidly circulating under pressure and the sudden change of temperature resulting from their commingling tends to cause 90 the oil to crack.

The introduction of a catalyst, steam, hot gases, or a treatment agent such as bentonite, hydrated lime, etc., or of some combination of them, into the circulating hydrocarbons in the manner provided for, promotes cracking and the subsequent separation of vapors and gases.

I have shown and described an embodiment of my invention well adapted for my process, but my apparatus may be varied in form and 10 in detail without defeating its purpose, and my process may be worked with any suitable apparatus.

I claim:

- 15 1. The process of producing low-boiling-point hydrocarbons from higher-boiling-point hydrocarbons which comprises controlled positive rapid circulation of the hydrocarbons by mechanical means by suction through a primary bank of tubes with a pump and simultaneously forcing through a secondary bank of tubes with the same pump under conditions of temperature conducive to cracking and under frequently varying 20 super-atmospheric pressure, discharging the cracked products from said secondary bank of tubes into a vaporizing zone, separating vapors from unvaporized oil and returning the unvaporized oil to said primary bank of heating tubes for retreatment.
- 25 2. In an apparatus for the treatment of hydrocarbons for the production of low boiling-point hydrocarbons from high boiling-point hydrocarbons, the combination of a vaporizing chamber, two separate banks of heating tubes connected with the chamber, a single means of connection between the two banks of heating tubes, and a pumping device interposed in said means for providing 30 a controlled positive pulsative circulation of oil from the vaporizing chamber directly through the first bank of heating tubes and thence through the second bank of heating tubes back into the vaporizing chamber.

45 HOMER T. DARLINGTON.
